UNITED STATES PATENT OFFICE.

ERNEST G. H. SCHENCK, OF NEW YORK, N. Y.

DESIGN FOR A CUT STONE.

40,693.

Specification for Design.

Patented May 17, 1910.

Application filed February 12, 1910. Serial No. 543,642. Term of patent 14 years.

To all whom it may concern:

Be it known that I, ERNEST G. H. SCHENCK, a subject of the King of Belgium, and residing at New York city, New York, have invented a new, original, and ornamental Design for a Cut Stone, of which the following is a specification, reference being had to the accompanying drawings, forming a part thereof.

In the drawings, Figure 1 shows a top view of a stone with facets cut according to my design; Fig. 2 is a perspective view of the same; and Fig. 3 is a side elevation, the lower part of the stone being conventionally shown by dotted lines.

My design relates more particularly to the manner of cutting facets on the upper side of the stone. The stone is of the usual shape tapering slightly toward the top and toward the bottom from its girdle.

The chief feature of my design is in having the table or central upper portion cut

into the shape of a polygon, of more than four sides, and in having this polygon bounded on all sides by substantially pentagonally-shaped facets, the facets themselves being outlined by straight edges. The facets bounding the polygonal table, although pentagonal as shown, have bases alternately narrow and broad. The facets having the narrow base resemble substantially a diamond-shaped figure.

Since my design does not relate to the lower part of the stone, this part is merely shown conventionally in dotted lines in Fig. 3.

I claim—

The ornamental design for a cut stone, substantially as shown and described.

ERNEST G. H. SCHENCK.
